10 Claims. (Cl. 33—79)

1

This invention relates generally to parallel motion drafting devices of the kind in which the several tools which the draftsman handles most frequently are embodied, in principle, in one unit to obviate the necessity of a draftsman reaching about for a required tool and thereby enabling the draftsman to keep his attention concentrated directly upon the drawing. More particularly the invention relates to parallel motion drafting devices of the band and pulley type although not so limited.

Drafting devices of this character are common in which an arm, broadly speaking, is articulated and whereof adjacent ends of two arm sections are pivoted together, the free end of one arm section being secured to the remote side of a drafting board while the free end of the other arm section is provided with a head comprising a protractor and straight-edges which are in fixed angular relation to move about the center of the protractor as an axis. Where a drafting device of this character is used upon a drawing board which is disposed in an inclined plane, the weight of the free arm and/or the head on the free end thereof is likely to cause the angle between the two arm sections to become more obtuse. A counterbalance has heretofore been proposed as an expedient to counteract the weight of the arm.

While the vertical and horizontal lines on a drawing may be perpendicular to one another, it is sometimes found, where changes are to be made to the drawing and it is again affixed to a drawing board for that purpose, that such vertical and horizontal lines are each at a slight and equal angle to the respective vertical and horizontal straight-edges carried by the drafting machine to be used by the draftsman about to make changes on or additions to the drawing. Shifting the drawing on the drafting table so that the base line thereof coincides with the straight-edge about to be used is not always practical.

One object of the present invention is to provide a drafting machine whereof the straight-edges may be adjusted to conform to the lines already drawn. Such an adjustment is commonly referred to as a base line adjustment. In carrying this aspect of the invention into effect, the instrumentalities maintaining the straight-edges in orientation, in this instance, an endless belt and pulley, are capable of being angularly shifted to that degree necessary to cause a straight-edge to coincide with a given base line.

It is also an object of the invention to enable a draftsman to work from any base line from horizontal to vertical up or vertical down or from

2

any base line intermediate between these verticals. By this invention, the straight-edges may be so set as to conform to the angularly disposed base line and the protractor adjusted so that the base line is indicated at zero on the scale of the protractor.

Another object of the invention is base line adjusting means enabling any degree of adjustment necessary within wide limits. Accordingly, 10 the means maintaining the straight-edges in orientation are mounted for movement independently of the anchor.

A further object of the invention is a drafting machine anchor in which the orientation of the 15 straight-edges may be readily effected by a manipulation at the anchor. To this end, in one aspect of the invention, a freely rotatable anchor pulley is latched in adjusted position to the anchor.

20 It is also an object of the invention to provide devices which will permit substantially unlimited adjustment of the base line. In carrying out this aspect of the invention, the anchor pulley is so mounted for rotation as to be rotatable through 25 any desired angle usually more than 180° and up to substantially 360°. This is dependent upon the relation of the size of the pulley, the length of the arms, and the initial position of adjustment and/or relative location of the means used to secure and/or determine the tension of the endless bands.

Yet another object of the invention is positioning means for the anchor pulley operable at substantially any degree of rotation thereof and 35 which is readily manipulated by the draftsman without requiring the use of tools.

Again, it is sought by this invention to permit maximum adjustment of an anchor pulley and band, while at the same time obviating damage to the band were a turnbuckle or other joining 40 means for the ends of a band to ride up on a pulley. To this end, stop means are provided limiting rotation of both the anchor pulley and the drafting machine arm about the anchor, as 45 will be described hereinafter.

The invention also seeks base line adjusting means which are practical from the standpoint of simplicity of manufacture and convenience and accuracy in use.

50 These and other objects of the invention and the means for their attainment will be more apparent from the following detailed description, taken in connection with the accompanying drawings illustrating one embodiment by which 55 the invention may be realized and in which:

Figure 1 is a view in perspective showing a drafting machine according to this invention attached to a drafting board which is indicated in broken lines, while the drawing and one of the lines thereon is shown in full lines;

Figure 2 is a view showing the anchor of a drafting machine attached to the edge of a drawing board, parts being in vertical section to show details of construction;

Figure 3 is a vertical sectional view taken in the plane indicated by the line 3-3 of Figure 2, looking in the direction of the arrows and showing details of construction; and

Figure 4 is a transverse sectional view taken in the plane indicated by the broken line 4-4 of Figure 2, looking in the direction of the arrows.

The anchor of this invention is illustrated as comprising an elongated housing 5 formed with a straight wall 7 provided with bosses 8 adapted to engage the side of a drafting board 9 and particularly the remote side 11 thereof. On the drafting board 9 is shown a drawing 10 on which one of the horizontal lines of the drawing is indicated at 12. Such a line 12 may be referred to as a base line of the drawing to which a straight-edge 14 must be made to coincide in order that the orientation of the straight-edges may correspond to that of the lines on the drawing.

Each end of the housing 5 is provided with a bracket 13 in which is rotatably mounted a clamping screw 15 adapted to engage the underneath surface of the drafting table. Above the housing 5 and preferably centrally thereof is conveniently located a generally cylindrical or tubular portion 17 shown as comprising a forwardly extending portion 19 adapted to rest upon the table and, with the clamping screws, clamping the anchor to the table. Within the tubular portion 17 are vertically spaced anti-friction devices for a pivot pin 21 on which is fixedly mounted by key 22 the end 23 of one arm of the drafting device. The anti-friction devices are conveniently the balls 24 and ball races 25 carried by the pin 21 and coating ball races 29 carried with the tubular portion 17. Races 25 are spaced by a sleeve 27 surrounding the pin.

A pulley 31, together with the endless band 33 in arm member 1, operates through the lower arm member 2 and head 3 as means for maintaining the straight-edges 14 in orientation. Arms 1 and 2 are herein sometimes collectively referred to in the singular. The pulley 31 is shown as formed with a hub portion 35 terminating in an inwardly extending annular lip 37 which supports the outer race 39 of a ball bearing, to which ball race 39 the pulley 31 is, conveniently, fixedly held as, for instance, by the head of a screw 41 on the upper side of the pulley and overlying the ball race. Obviously other ways to secure the pulley to one element of the anti-friction device may be availed of. The inner race 45 of the ball bearing turns with the pin 21 which supports the arm 23. The arm 23 is mounted so as to be freely rotatable within limits with respect to both the pulley and the housing.

Means to counterbalance the weight of the arms are illustrated generally as a leaf spring 47 engaged by a roller 49 mounted eccentrically of the pivot pin 21. Such counterbalancing device is shown, described and claimed in Patent No. 2,266,785, granted December 23, 1941, to C. W. Keuffel, and details of the counter-balancing device are therefore not illustrated or described herein as they form no part of the instant invention.

It is proposed, according to this invention, to adjust the orientation of the straight-edge means by adjustment of the means maintaining the straight-edge means in orientation, to wit: the anchor pulley and the band. As shown, the pulley 31 is mounted so as to be freely rotatable within limits with respect to the anchor. Latching means, so-called, are carried by the anchor to fix the pulley in adjusted position and thereby maintain the straight-edges in the desired orientation. In the illustrated embodiment, the pulley is shown as formed in its lower face with an annular groove 51, T-shaped in cross-section, with the narrowest portion 53 of the groove opening through the lower face of the pulley. Thus shoulder means, shown as the spaced shoulders 55, are conveniently upwardly facing and may comprise means to coact with manually actuated clamping or latching means carried by the anchor and shown on the order of a T-bolt. In the illustrated embodiment, see Figure 2, the head of the T-bolt may be a plate 57, which may be arcuate in plan, is disposed in the slot 51 and rests on the shoulders 55. The plate 57 is mounted on the end of a threaded rod or shank 59 which is journalled in a boss 61 on the tubular portion 17 of the anchor. A collar 65 is threaded on the end of the shank 59 and is so positioned as to bear lightly against a washer 63 or the equivalent, on the shank, when the plate 57 is freely movable with respect to the slot or shoulder therein. To this collar 65 is pinned an actuating handle 67, as by pin 68. Thus, when the pulley has been turned to the position at which a straight-edge is in the desired orientation, the handle 67 may be turned, causing the collar 65 to ride up on the shank 59 thereby camming down the shank 59 and retaining the plate 57 in frictional engagement with the shoulders 55 of the groove and clamping the pulley against the frame of the anchor to hold it in the desired position of adjustment. Since the slot is continuous, the head lies in the slot at any position of adjustment of the pulley. The handle is of such proportion that it will abut against the anchor if rotated beyond that degree necessary to release the head from the groove shoulder and thus cannot be screwed completely off the shank. By such clamping device the pulley may be permitted to turn as the straight-edges are brought into orientation until the desired orientation is attained, and then, by turning the handle 67, the pulley and belt may be fixed with respect to the anchor so as to maintain the straight-edges in orientation. The handle 67 is particularly convenient for such purpose since the draftsman may turn the handle to clamp or unclamp the pulley with the fingers of one hand while using the other hand to adjust the straight-edges.

The clamping device may be readily assembled with the pulley in any convenient manner. As shown in Figure 4 the groove portion 53 of groove 51 in the pulley 31 is formed with a widened passage portion 73 leading from its bottom face to the groove 51 and of the same transverse shape 65 as the clamping plate 57. Before the pulley is put in place, the clamping plate 57 and shaft 59 may be passed upwardly through the passage portion 73 and the pulley and clamping plate 57 moved relative to one another through approximately 180°. The shank 59 may be passed through lug 61 and the handle 67 affixed to the shaft 59 to hold the clamp member from displacement. The band 33 which passes around the pulley is usually made of a ribbon of steel having the ends secured as by a turnbuckle, not

shown, to insure the band engaging the pulley with a driving friction. Since the anchor pulley 31 in the machine as described is rotatable when the clamping means is released, it is desirable to limit such rotation of the pulley so as to prevent damage or breakage of the bands by the turnbuckle riding up on the pulleys. It is desirable therefore, to limit the rotation of the pulley at least to such extent as to prevent damaging contact of the means joining the bands and the pulleys. Accordingly, two pins or lugs 60 (Figures 2 and 4) are mounted on the underside of pulley 31 so that when the pulley is rotated in either direction relative to the anchor, one of the lugs 60 will engage the boss 61 and thereby limit the movement of the pulley 31 with respect to the anchor. From the position of the pulley as illustrated in Figure 4, this rotation would be a little more than ninety degrees in both directions.

It will be observed that the passage portion 73 is normally on the opposite side of the axis of the pulley from the boss 61 and spaced approximately equiangularly from the pins 60. Thus, the clamping plate 57 never traverses the enlarged portion 73 of the groove 51-53 in the normal operation of the machine.

When the pulley 31 is latched to the anchor, rotation of the arm 23 about the anchor might also cause the joining means of the bands to ride up on a pulley in the same manner as the rotation of the unlatched pulley with respect to the anchor. The combined effect of rotation of the pulley 31 about the anchor for adjustment of the straight-edges to a desired base line and rotation of the arm 23 about the anchor in the normal use of the machine might be cumulative or in opposition depending upon the direction of the rotation of the pulley for base line adjustment and the direction of rotation of the arm in the use of the machine. To prevent damage to the machine, it is desirable to limit the rotation of the arm 23 about the anchor to some predetermined angle such as slightly less than 360°. To this end, in the illustrative embodiment, a pin or lug 69 is disposed radially on the pivot pin 21 and a stop 71 fixed in the anchor at the desired place so that the pin 69 turning in either direction with the sleeve 27 and pivot pin 21 engages the stop 71 and thereby prevents the arm 23 from rotating through more than slightly less than 360°.

It will thus be seen that an anchor is provided for drafting machines in which the proper positioning of the straight-edges is effected by an adjustment self-made, so to speak, by the instrument itself and requiring only that the pulley be released and the straight-edges be turned to coincide with a base line whereupon the straight-edges are latched in adjusted position by a manipulation at the anchor.

Various modifications will occur to those skilled in the art in the disposition and configuration of the component elements going to make up the invention as a whole as well as in the mechanical movements adapted to effect the adjustment and fixing of the anchoring pulley, and no limitation is intended by the phraseology of the foregoing description or illustrations in the accompanying drawings except as indicated in the appended claims.

What is claimed is:

1. In a drafting machine of the wheel and band type having an anchor, the combination with a pulley therein about which the band passes in maintaining the straight edge means in orientation:

of means mounting said pulley for free rotation, said pulley being formed with an annular shoulder, clamping means disposed on the shoulder, and actuating means carried by the anchor to actuate said clamping means and cause said clamping means to engage on the shoulder and retain the pulley in adjusted position.

2. In a drafting machine of the wheel and band type having an anchor, the combination with a pulley therein about which the band passes in maintaining the straight edge means in orientation: of means mounting said pulley for free rotation, said pulley being formed with an annular groove having a shoulder, and adjustably mounted means carried by the anchor and engaging the shoulder to retain the pulley in adjusted position.

3. In a drafting machine of the wheel and band type having an anchor, the combination with a pulley therein about which the band passes in maintaining the straight edge means in orientation: of means mounting said pulley for free rotation, said pulley being provided with a shoulder and means carried by the anchor and engaging the shoulder to retain the pulley in adjusted position.

4. In a drafting machine of the wheel and band type having an anchor, the combination with a pulley therein about which the band passes in maintaining the straight edge means in orientation: of means mounting said pulley for free rotation, said pulley being formed with an arcuate groove concentric with the axis of the pulley and T-shaped in cross-section and clamping means T-shaped in cross-section carried by the anchor and disposed in the groove to retain the pulley in adjusted position.

5. In a drafting machine of the wheel and band type having an anchor, the combination with an arcuately movably mounted member therein about which the band passes in maintaining the straight edge means in orientation: of the arcuately movably mounted member provided with an arcuate slot, clamping means carried by the anchor means and passing through the slot and engaging the arcuately movably mounted member, and manually actuatable lever means to draw said clamping means into clamping engagement with said arcuately movably mounted member to retain said arcuately movably mounted member in adjusted position.

6. In a drafting machine of the wheel and band type having an anchor, the combination with an arcuately movably mounted member therein about which the band passes in maintaining the straight edge means in orientation: of said arcuately movably mounted member provided with an arcuate slot, clamping means carried by the anchor means comprising a helically grooved shaft disposed in the slot in the arcuately movably mounted member, a clamping plate on the shaft, sleeve means on the shaft and coacting lever means to draw the plate into clamping engagement with the arcuately movably mounted member and retain said member in adjusted position.

7. In a drafting machine of the wheel and band type having an anchor, the combination with a pulley therein about which the band passes in maintaining the straight edge means in orientation: of manipulatory means carried by the anchor and engaging the pulley at a selected one of a plurality of positions to maintain said last-named means in adjusted position and means to limit the movement of the pulley comprising a

stop on the anchor and a coating stop on the pulley.

8. In a drafting machine of the wheel and band type having an anchor, the combination with a pulley therein about which the band passes in maintaining the straight edge means in orientation: of an annular passage in the pulley having a surface, means in the passage carried by the anchor and adapted to engage the surface to retain the pulley in adjusted position.

9. In a drafting machine of the wheel and band type having an anchor, the combination with a pulley therein about which the band passes in maintaining the straight edge means in orientation: of at least one arm pivotally mounted on said anchor, an annular passage in the pulley having a surface, means in the passage carried by the anchor and adapted to engage the surface to retain the pulley in adjusted position, said anchor also comprising stop means limiting relative rotation of the arm.

10. In a drafting machine of the wheel and

band type having an anchor, the combination with a pulley therein about which the band passes in maintaining the straight edge means in orientation: of an annular passage in the pulley having a surface, means in the passage carried by the anchor and adapted to engage the surface to retain the pulley in adjusted position, said anchor also comprising stop means and a lug on said pulley engageable by the stop means and limiting rotation of the pulley in either direction.
